UNITED STATES PATENT OFFICE.

ENOCH P. STEVENS, OF MORGAN PARK, ILLINOIS.

ROLLER-GRAVE.

1,127,939.

Specification of Letters Patent.

Patented Feb. 9, 1915.

Application filed May 20, 1912. Serial No. 698,391.

To all whom it may concern:

Be it known that I, ENOCH P. STEVENS, a citizen of the United States, residing at Morgan Park, in the county of Cook and State of Illinois, have invented certain new and useful Improvements in Roller-Grates, of which the following is a specification.

My invention relates to roller grates and particularly to grates of this character adapted to operate by gravity and mechanically to automatically feed coal in the stoking of locomotives and other furnaces. In such cases it is important that during the progressive combustion of the fuel the same shall be caused to travel continuously from the point of introduction at the rear of the fire box to the point of discharge to the ash pit at the front of the same, and moreover that the introduction of air to the fuel shall be graduated to the demand in order to produce perfect combustion, less being required as the fuel is more nearly reduced to ash. It is also found that with the cheaper grades of fuel there is a tendency to coke and thus impair or delay the complete consumption of the same and cause the grate to clog or the travel of the fuel bed to become intermittent or to cease entirely at certain points within the fire box requiring manual breaking up and agitation. Having these objects and conditions in view I arrange the grate at an incline so as to utilize the action of gravity in feeding the fuel forward and I also provide rotary grate bars arranged in tandem each of which in turn receives the fuel from the one preceding and passes it on to the succeeding bar, such grate bars being arranged to admit to the fuel air in quantities gradually decreasing from the rear to the front to accord with the requirements of progressive combustion. I also preferably arrange, in the spaces between the successive grate bars, trip bars operated intermittently to throw the superjacent fuel forward on to the next succeeding grate bar whereby the feeding is rendered more certain and the tendency to coke and clog is overcome.

In the accompanying drawings forming a part of this application and to which reference will be had in the further detailed description of the same, I have illustrated by way of example a preferred and modified embodiment of the invention.

In these drawings, Figure 1 is a fragmentary longitudinal section through the fire

box of a locomotive showing my improved roller grate in side elevation. Fig. 2 is a detail plan view of certain of the grate elements with parts broken away. Fig. 3 is a fragmentary vertical section through a pair of adjacent grate bars and the interposed trip bar. Fig. 4 is a view showing the same parts as Fig. 3 but in side elevation. Fig. 5 is a view similar to Fig. 2 but of a modification. Fig. 6 is an irregular longitudinal vertical section through Fig. 5, and Fig. 7 is a detail view showing a further slightly modified form of grate bar.

In the drawings and having more particular reference to Figs. 1 to 4 inclusive, reference numeral 11 designates the water space of a boiler having the legs 12 and 13 depending respectively in the rear of and at the front of the fire box 14, within which is arranged the brick arch 15 resting upon pipes 16 which establish a communication between the legs 12 and 13 through the combustion area. The rear portion of the fire box merges into the hopper 17 through which coal is supplied and directed by the inclined lower wall 18 upon the grate which latter forms the subject matter of the present application and will now be described in detail. A series of grate bars 19, 20, 21, 22, 23 and 24 are arranged transversely of the fire box in the lower portion of the same in spaced tandem relation as shown and at an inclination from the rear to the front of the fire box. This series of grate bars serves to feed the fuel progressively from the rear to the front of the fire box and to deliver the unconsumed portions to the ash discharge bar 25 which occupies a position in line with the fuel grate bars and at the extreme front end of the fire box, it being understood that the number of grate bars may be increased or diminished according to the size of the fire box and the nature of the fuel as conditions may demand. Each of the fuel bars comprises a shaft which in its medial portion 26 is angular in cross section, while at its end portions 27, 27 it is advantageously circular in cross section and journaled in suitable bearings in the side walls of the fire box or in bearing plates 28, 28 built into the fire box structure. Upon the angular portion 26 of each of the shafts are disposed a number of unit sections each composed of a plurality of disks 29 spaced apart by lateral lugs 30 so as to provide a passageway between ad-

jacent disks for air from the space beneath the grate bars to the fuel area above the same. The spaces between the disks upon the successive shafts gradually decrease 5 from the rear to the front so as to provide a gradually decreasing area for the admission of air, until the last grate bar 24 is reached and this grate bar may be made substantially or entirely solid or impervious 10 to the passage of air, it being, however, also preferably built up of unit sections to facilitate the assembling of the same so as to produce a grate bar of varying length to fit within fire boxes of different widths, and 15 to permit the individual grate bars and single sections to be independently removed and renewed as occasion may require. Immediately in front of the grate bar 24 and operating in close peripheral relation there- 20 to is similarly mounted the ash discharge bar 25 which is provided with radially ex- tending vanes 31. In my preferred con- struction the grate bars 19—24 are spaced 25 apart sufficiently to receive in the inter- spaces trip bars 32 which are substantially tri-angular in cross section and have their ends journaled at 33 in the bearing plates 28. These trip bars are provided along their rear edges with a series of tongues 30 34 which take into the spaces between the disks 29 of the preceding grate bar but do not extend into said spaces far enough to reach the lugs 30. Upon the front edge each of the trip bars 32 is provided with a 35 pair of ribs or shoulders 35, 35 which take into the spaces between the disks of the suc- ceeding grate bar and extend into the path of the lugs 30 so as to contact therewith during the rotation of the grate bar where- 40 by the trip bar will be rocked in its bear- ings. At its two ends each trip bar is pro- vided with a crank arm 36 to which is at- tached one end of a coil spring 38, the other 45 end of which is attached to a suitable fixed support. Upon one end of each of the 50 grate bars 19 to 24 is mounted a ratchet wheel 39, and a ratchet arm 40 is pivoted upon the end 27 of each shaft. Each of 55 these ratchet arms carries a pawl 41 in operative engagement with the teeth of the ratchet 39, the end of each of the ratchet arms 40 being pivoted at 42 to a crank rod 43 pivoted at 44 to the crank disk 45 which is driven by any suitable source of power 60 and which through the ratchet and pawl mechanism rotates the grate bars 19 to 24 in a uniform direction step by step. Upon the opposite end of the grate bar 24, its shaft 27 has keyed thereon a gear 46 which is in mesh with a similar gear 47 keyed to the shaft of the ash discharge bar 25 where- 65 by the bar 25 is caused to partake of the rotary movement of the bar 24 but in the opposite direction.

65 From the foregoing description it will be

readily understood that the step by step ro- 70 tary movement of the grate bars 19 to 24 will cause the fuel resting thereon to be fed toward the front of the fire box from each grate bar on to the substantially flat 75 upper face of the trip bar arranged im- mediately contiguous thereto, the tongues 34 serving to catch any fragments of fuel which may have lodged between the outer edges of the disks. As the grate bars 20 80 to 24 rotate the lugs 30 thereof will engage the cam face of each of the ribs or shoul- ders 35 and lift the same rocking the trip bar 32 slowly toward the fuel being dis- charged thereon, such rocking serving at 85 the same time to place the spring 38 under increased tension. As soon as the lug 30 clears the upper edge of the rib 35 the spring 38 will draw the latter quickly downward and rock the trip bar back to its 90 former position imparting to the fuel upon the trip bar a sharp throw toward the front down the incline on to the surface of the next succeeding grate bar, the fuel being thus carried onward by the surface of this 95 grate bar to be discharged on the next trip bar, this operation being repeated inter- mittently during the step by step rotation of the grate bars. These trip bars 32 serve not only to facilitate the feed of the fuel 100 progressively over the grate but the tripping of the same serves to break up any coal which would otherwise tend to coke and ride intact within the trough formed between adjacent grate bars. The tongues 105 34 and the ribs 35 also not only serve their respective functions as hitherto described but they serve as heat radiating means by which the trip bars are kept cool, a similar function being performed by the lugs 30 110 between the respective disk which go to make up the unit sections of the grate bars.

In using some kinds of fuel it has been found possible to omit all or a portion of the trip bars 32, in which case the adjacent 115 grate bars are journaled sufficiently close together that the peripheries of the disks are spaced but a slight distance apart, in which case the fuel is fed directly from the surface of one grate bar on to that of 115 the next succeeding grate bar. Under such circumstances it has also been found to be advantageous to arrange the disks in suc- 120 ceeding grate bars in staggered relation as shown in Fig. 5 so that the under portion 120 of the fuel which upon the one grate bar rested upon the impervious portion of the same will when passing over the next grate bar occupy a position above the spaces be- 125 tween the disks so as to be exposed to the air currents arising therethrough. This staggered relation of the disks may ad- vantageously be employed also in connec- 130 tion with the interposed trip bars although the agitation of the fuel by said bars ren-

ders this feature less important in that form of construction and arrangement.

Where the trip bars 32 are omitted it is sometimes found to be advantageous to roughen the peripheries of the disks comprising the grate bars as indicated in Fig. 7, so as to obviate any tendency of the grate bars to rotate freely beneath the fuel without engaging and carrying the same forward.

In both forms of construction described above the ash discharge bar 25 by its vanes 31 engages the ashes delivered from the grate bar 24 and carries the same downwardly between the bars 24 and 25 discharging the same in the ash pit beneath the fire box. This ash discharge bar 25 operates in such close relation to the bar 24 and to the front wall of the fire box as to practically exclude the entrance of the air to the front of the fire box from below the same.

While I have described with a considerable degree of particularity the various features entering into an illustrated embodiment of the invention in order that the invention might be readily understood, it will be obvious that still further modifications may be made without departing from the invention or sacrificing its material advantages.

I claim—

1. In a grate, a series of fuel bars comprising disk-like sections spaced apart laterally by interposed lugs, the successive bars of the series having their disk sections approached more nearly together to gradually reduce the air passage therebetween, a series of trip bars arranged in the interspaces between the fuel bars, the trip bars having along one edge tongues taking into the spaces between the disks of the preceding fuel bar and along their opposite edge shoulders having a lower cam face extending between the spacing lugs of the next succeeding fuel bar, yielding means tending to tilt the trip bars toward the front of the grate, and means to rotate the fuel bars step by step in a common direction to feed the fuel from each of said bars on to the upper face of the next succeeding trip bar and toward the front of the grate, the lugs of the fuel bars engaging the lower cam face of the shoulders and tilting the trip bars in an opposite direction, the yielding means serving to rock the trip bars sharply when released to throw the fuel therefrom on to the next succeeding grate bar, substantially as described.

2. In a grate, a series of fuel bars comprising disk-like sections spaced apart laterally by interposed lugs, the successive bars of the series having their disk sections approached more nearly together to gradually reduce the air passage therebetween, a series of trip bars arranged in the interspaces be-

tween the fuel bars, the trip bars having along their rear edge tongues taking into the spaces between the disks of the preceding fuel bar and along their front edge shoulders having a lower cam face extending between the spacing lugs of the next succeeding fuel bar, yielding means tending to tilt the trip bars toward the front of the grate, means to rotate the fuel bars step by step in a common direction to feed the fuel from each of said bars on to the upper face of the next succeeding trip bar and toward the front of the grate, the lugs of the fuel bars engaging the lower cam face of the shoulders and tilting the trip bars in an opposite direction, the yielding means serving to rock the trip bars sharply when released to throw the fuel therefrom on to the next succeeding grate bar, an ash discharge bar arranged parallel and closely adjacent to the last grate bar and provided with radial vanes, and means to rotate said ash discharge bar in a direction opposite to that of the fuel bars, substantially as described.

3. In a grate, a series of fuel bars journaled in successive parallel spaced relation, a ratchet wheel fixed upon one end of each of the bars, a ratchet arm pivoted concentrically of each ratchet wheel, a pawl carried by the ratchet arm in engagement with the teeth of its ratchet wheel, a crank rod connecting the free ends of the several ratchet arms, a suitably driven crank member connected to the crank rod, a series of trip bars journaled in the spaces between the fuel bars, a crank arm carried by each trip bar, a spring secured to said crank arm and to a suitable support, and means carried by the fuel bars to rock the trip bars in opposition to the spring, whereby the fuel bars are driven step by step in unison and the trip bars sharply rocked at intervals by the tension of their springs, substantially as described.

4. In a grate, a series of fuel bars journaled in successive parallel spaced relation, a ratchet wheel fixed upon one end of each of the bars, a ratchet arm pivoted concentrically of each ratchet wheel, a pawl carried by the ratchet arm in engagement with the teeth of its ratchet wheel, a crank rod connecting the free ends of the several ratchet arms, a suitably driven crank member connected to the crank rod, a series of trip bars journaled in the spaces between the fuel bars, a crank arm carried by each trip bar, a spring secured to said crank arm and to a suitable support, means carried by the fuel bars to rock the trip bars in opposition to the spring, whereby the fuel bars are driven step by step in unison and the trip bars sharply rocked at intervals by the tension of their springs, an ash discharge bar journaled in parallel relation to the frontmost of the fuel bars and provided with radial

vanes revolving closely adjacent to the periphery of said fuel bar, the frontmost fuel bar and ash discharge bar provided with intermeshing gears whereby the ash discharge bar is rotated in a direction opposite to that of the fuel bars, substantially as described.

5. In a grate, a series of fuel bars comprising disk-like sections spaced apart laterally by interposed lugs, a series of trip bars arranged in the interspaces between the fuel bars, the trip bars having along their front edge shoulders having a lower cam face extending between the spacing lugs of the next succeeding fuel bar, yielding means tending to tilt the trip bars toward the front of the grate, and means to rotate the fuel bars step by step in a common direction to feed the fuel from each of said bars on to the upper face of the next succeeding trip bar and toward the front of the grate, the lugs of the fuel bars engaging the lower cam face of the 45 shoulders and tilting the trip bars in an opposite direction, the yielding means serving to rock the trip bars sharply when released to throw the fuel therefrom on to the next succeeding grate bar, an ash discharge bar arranged parallel and closely adjacent to the last grate bar and provided with radial vanes, and means to rotate ash discharge bar in a direction opposite to that of the fuel bars, substantially as described.

6. In a grate, a series of fuel bars comprising disk-like sections spaced apart laterally by interposed lugs, a series of trip bars arranged in the interspaces between the fuel bars, the trip bars having along their rear edge tongues taking into the spaces between the disks of the preceding fuel bar and along their front edge shoulders having a lower cam face extending between the spacing lugs of the next succeeding fuel bar, yielding means tending to tilt the trip bars toward the front of the

grate, means to rotate the fuel bars step by 40 step in a common direction to feed the fuel from each of said bars on to the upper face of the next succeeding trip bar and toward the front of the grate, the lugs of the fuel bars engaging the lower cam face of the 45 shoulders and tilting the trip bars in an opposite direction, the yielding means serving to rock the trip bars sharply when released to throw the fuel therefrom on to the next succeeding grate bar, an ash discharge bar arranged parallel and closely adjacent to the last grate bar and provided with radial vanes, and means to rotate ash discharge bar in a direction opposite to that of the fuel bars, substantially as described.

7. In a grate, a series of fuel bars, each of which comprises a plurality of circular, disk-like sections laterally spaced apart from each other, means for rotating said 60 fuel bars, a series of trip bars arranged in the spaces between the fuel bars, each of said trip bars having a plurality of tongues extending into the spaces between the disk-like sections of said fuel bars, a cam on each 65 of said trip bars, lugs on said fuel bars adapted to engage the cams of said trip bars at predetermined points in the rotation of said fuel bars, and a spring attached to each of said trip bars, whereby, when the 70 cam of each trip bar is released from the lug of the adjacent fuel bar, said trip bar will be sharply rocked and will advance fuel from one fuel bar to the next.
